United States Patent Office

Des. 205,150
Patented June 28, 1966

205,150

FRYPAN OR THE LIKE

Ross E. Cornwell, Jr., Chicago, and Frank J. Di Sesa, Jr.,
Lombard, Ill., assignors to Sunbeam Corporation, Chicago, Ill., a corporation of Illinois

Filed July 6, 1965, Ser. No. 86,023

Term of patent 14 years

(Cl. D44—1)

Fig. 1.

Fig. 2.

Fig. 3.

Fig. 4.

FIG. 1 is a perspective view of a frypan or the like showing our new design;

FIG. 2 is a side elevation view thereof;

FIG. 3 is a top plan view thereof; and

FIG. 4 is an end elevation view thereof.

The dominant features of the design are shown in solid lines.

We claim:

The ornamental design for a frypan or the like, as shown and described.
